FUEL DISTRIBUTING CHAMBER

William Thompson Hanna, Cincinnati, Ohio

Application June 15, 1938, Serial No. 213,809

2 Claims. (Cl. 110—105.5)

This invention relates to locomotive stokers and more particularly to fuel distributing mechanism disposed in the proximity of the fuel delivery entrance to a locomotive fire box.

One of the objects of this invention is to provide fuel distributing apparatus which is simple and sturdy in construction, and which evenly distributes non-uniform particles of fuel over the fire bed. Another object is to provide apparatus of the above nature which utilizes blasts of fluid under pressure to distribute the fuel and which provides more nearly uniform blasts as desired. Other objects will be in part apparent and in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawings in which is shown one embodiment of this invention,

Figure 1 is a front elevation (looking from within the fire box) of the fuel distributing apparatus installed adjacent the firing opening;

Figure 2 is a top plan view of the apparatus shown in Figure 1;

Figure 3 is a bottom plan view of the blast chamber shown in Figure 1, the bottom cover thereof being removed;

Figure 4 is a fragmentary side elevation of the apparatus shown in Figures 1 and 2, a portion of a fuel delivery conduit being shown in section;

Figure 5 is a vertical section taken along the line 5—5 in Figure 2;

Figure 6 is a horizontal section taken along the line 6—6 in Figures 1 and 4;

Figure 7 is a vertical section taken along the line 7—7 in Figures 2 and 3;

Figure 8 is a vertical section taken along the line 8—8 in Figures 2 and 3;

Figure 9 is a vertical section taken along the line 9—9 in Figure 3; and,

Figure 10 is a vertical section taken along the line 10—10 in Figure 3.

Similar reference characters refer to similar parts throughout the several views of the drawings.

In stoking locomotives with coal, "run of the mine" coal is generally brought through a transfer conduit from beneath a tender to the firing opening of the locomotive fire box where it is distributed over the fire box by means of steam

blasts. "Run of the mine" coal as it is put into the tender consists of very fine particles all the way up to large lumps. This coal in passing to the transfer conduit is crushed so that the lumps are at least reduced to a certain maximum size. Thus the coal, on reaching the firing opening, consists of fine, almost dust-like particles, and larger particles up to lumps which may be two inches in diameter. The coal thus presented to the fire box must be distributed over it uniformly and in such manner that the fine coal is not blown out of the stack to give black smoke and the accompanying loss, and so that the larger lumps will not all pile up in the fire box adjacent the firing opening. Also, the coal must be fired evenly over the fire box, which is oftentimes as large as ten feet long and eight feet wide or even larger. If it is not distributed evenly and allows a thin spot to form in the bed, the draft may burn out that spot and so short-circuit the air flow through the rest of the bed, causing the whole fire to go down. Or if the coal piles up in any particular place, thereby stopping the draft from coming through, the coal does not burn sufficiently rapidly and continues to pile up unburned coal, forming clinkers.

Thus, the importance of proper distribution of the coal over the fire bed can readily be appreciated, and the difficulty of distributing this heterogenous coal may be understood.

In my Patent No. 2,044,001, I have described a blast chamber and distributing plate which is designed to screen the coarse particles from the finer particles so as to distribute the coarser particles with high pressure jets and the finer particles with a low pressure jet, at the same time to so blanket the low pressure jet carrying the fine fuel as to prevent that fuel from leaving the stack unburned. To obtain the desired degree of efficiency from this blast chamber, however, it is desirable to have uniformity in the strength of the various related steam blasts and with the present invention this desired uniformity of blast is made practical in an inexpensive and commercially practical device.

Referring now to Figures 1 and 2 of the drawings, the fuel distributing apparatus comprises a distributing device or blast chamber generally indicated at 20, and a distributor plate coating therewith generally indicated at 59. Blast device 20 has a pair of supporting arms 21 and 22 pivotally connected respectively to steam pipes 23 and 24 which suspend the blast chamber within a firing opening 25. With reference to Figure

4, fuel distributing device 20 is suspended (as described in the above-mentioned patent) adjacent the delivery end or spillway of a fuel conduit 26, only a part of which is shown, which delivers fuel to device 20 from which the fuel is blown by a fluid such as steam under pressure over the fire bed in the fire box.

Referring back to Figure 1, fuel distributing device 20 includes a plurality of fingers 27 each of which has a jet 28 communicating with a symmetrically shaped high pressure steam chamber 29 (Figure 6) having a central opening 30 in the back thereof which connects the chamber to a conduit 31 (see also Figure 5) communicating with steam pipe 23 by a channel 32 (Figure 6) formed in supporting arm 21. Preferably steam chamber 29 tapers towards its extremities 29a and 29b to effect a uniformity of steam pressure throughout the chamber. Steam channel 32 is connected in any suitable manner with a source (not shown) of high pressure steam. Fingers 27 are arranged in diverging fan-like formation so that steam supplied by pipe 23 (Figure 5) and flowing through channel 32, conduit 31 and opening 30 (Figure 6) into chamber 29 is distributed in a fan-shaped blast by jets 28. As shown in Figure 7, jets 28 project slightly downwardly and accordingly the steam blast is directed downwardly toward the fire bed rather than upwardly toward the stack, for purposes described herein-after.

Opening 30 which connects steam conduit 31 with chamber 29 is formed by a partition 33 which separates conduit 31 from chamber 29 and a partition 34 which separates chamber 29 from a steam duct 35. Because of the location of opening 30 and partition 34, the steam is delivered substantially centrally into chamber 29 in which it may expand somewhat before flowing through fingers 27. The central disposition of opening 30, the change of direction of steam flow afforded by partition 34, and the tapered ends 29a and 29b of chamber 29 result in a substantially uniform pressure throughout the chamber, with the ultimate result that the pressure of the steam blast from each jet 28 is substantially uniform.

Referring back to Figure 1, distributing device or blast chamber 20 includes a horizontal steam orifice or slot jet 36 which is arcuate in shape and disposed below the plane of jets 28 (Figures 7 and 8). Slot jet 36 is formed by a downwardly extending portion 37 of blast chamber 20 and the edge portion 38a of a bottom cover plate 38 which is secured to the blast chamber by screws 39 or the like. As shown in Figure 5, blast chamber 20 has a recessed portion which with bottom cover plate 38 forms a low pressure steam chamber 40 communicating with slot jet 36 (Figure 7). Steam flows into chamber 40 from duct 25 through a plurality of ports 41 formed in a partition 42 of blast chamber 20 which separates chamber 40 from chamber 29 and from steam duct 35. Steam duct 35 communicates with steam pipe 24 by way of a channel 43 formed in supporting arm 22; channel 43 being suitably connected to a source (not shown) of low pressure steam. These ports 41 are arranged substantially centrally of chamber 40 (Figure 3) preferably at the rear thereof so that steam flowing through the ports impinges directly against bottom plate 38 (Figures 5 and 7) and spreads uniformly throughout the chamber.

I have found that by providing the plurality of symmetrically arranged ports 41 between the chamber 29 and the chamber 40 a more nearly

uniform blast is obtained from the jet 36 in spite of such irregularities of shape as may occur in chamber 40 due to imperfections of casting. These ports and the baffles 44, 45 and 46 break the steam flow into a relatively large number of paths.

As will be noted in greater detail hereinbelow, fuel distributing device or blast chamber 20 (Figure 1) includes a plurality of finger jets 28 and a slot jet 36 disposed below the finger jets. Assuming that jets 28 and slot jet 36 project blasts of steam the intensity of each of which is uniform throughout its entire extent, all particles of fuel, regardless of their size, are projected by the two blasts into the fire box and are uniformly distributed over all portions of the fire bed.

Chamber 40 is provided with a suitable number of baffles 44, 45 and 46 which are proportioned and arranged to influence the distribution of steam throughout chamber 40 so as to effect a flow of steam through the entire extent of slot jet 36 at a substantially uniform pressure. Blast chamber 20 also includes a pair of jets 47 and 48 (Figures 2, 3 and 10) which preferably are arranged with their discharge ends in a plane slightly above that of slot jet 36, but below that of jets 28; the axis of jets 47 and 48 preferably being slightly inclined and laterally divergent. These jets also communicate with chamber 40 and accordingly are supplied with steam at the same pressure as that at all portions of slot jet 36. Baffles 44, 45 and 46 may be integral with blast chamber 20 (see Figures 7, 8 and 9) and extend downwardly therefrom against bottom plate 38, and preferably are symmetrically disposed throughout chamber 40 (Figure 3). Conveniently, one of baffles 44 is disposed adjacent and centrally of entry ports 41, the other baffles 44 being disposed laterally of the entry ports at a substantial distance therefrom. Each of baffles 45 is disposed laterally of the entry ports 41 between adjacent baffles 44 and baffles 46 may project into chamber 40 from the rear wall of the chamber on opposite sides of ports 41. It is to be understood, however, that this arrangement of the baffles is illustrative and may be modified in accordance with varying conditions.

It will now appear that steam flowing through pipe 24 (Figure 5) flows through channel 43, duct 35 and ports 41 into chamber 40 from which it flows at a substantially uniform pressure through slot jet 36 (Figure 1) and jets 47 and 48.

Suitably suspended within firing opening 25 (Figures 1, 2 and 4) is a fuel distributing plate 49 whose upper surface 50 is disposed below jets 28 and slot jet 36 and which is slightly inclined downwardly with respect to the planes thereof. The opposite sides of fuel distributing plate 49 are hollowed out to provide curved and sloping fuel channels 51—54 which terminate at each side of the plate; pockets 54 being aligned respectively with jets 47 and 48.

In operation, fuel particles of heterogeneous size are spilled from fuel conduit 26 (Figure 4) through firing opening 25 onto blast chamber fingers 27. The larger particles of coal ride down over these fingers until they fall off the ends thereof in front of the blast of steam shooting from jets 28. As noted above, these jets are slightly inclined downwardly and accordingly blow the particles of fuel downwardly onto the fire bed which precludes passage of fuel up the stack. Furthermore, as the blast of steam from the finger jets is of uniform intensity throughout its area, an even distribution of the larger fuel

particles is effected throughout the fire bed. The smaller fuel particles fall between fingers 21 into the path of the steam blast shooting from slot jet 36 which with its blast of even intensity spreads the fuel in a fan-like sheet over the fire bed.

Because the finer fuel particles are distributed by the sheet blast from the slot jet in a plane below the blast from finger jets 28, such particles are protected, by the downwardly expanding curtain of steam formed by the upper blast, from being carried upward and out of the stack. The slight inclination of finger jets 28 facilitates this protective action of the upper blast.

As shown in Figure 1, the size of the spillway opening at the top of blast chamber 20 is variable through the provision of a pair of slidable plates 52 and 53.

Accordingly it may be seen that I have provided fuel distributing apparatus which attains the several objects hereinabove set forth in a thoroughly practical and efficient manner.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. As an article of manufacture, a distributing device for a locomotive stoker for distributing over a fire box fuel fed thereto, said distributing device comprising a metal casting having a plurality of hollow fingers extending from the body of the casting in fan shape, said casting having a high pressure steam chamber therein communicating with said hollow fingers from within the casting for conducting steam thereto, said

casting having a recess formed on one side thereof, the upper wall of said recess having a plurality of centrally disposed orifices therein for the admission of steam thereto, a cover plate 5 for forming with said recess a low pressure steam chamber, the upper wall of said recess and said cover plate forming top and bottom sides for said low pressure steam chamber, means forming a longitudinal slot in said low pressure steam chamber through which steam may flow from said low pressure chamber, and means forming a plurality of baffles in said low pressure chamber extending from one of said sides to the other and disposed between said opening and said slot for so restricting the flow of steam to said slot that a uniform steam pressure exists in said low pressure chamber at the exit end of said slot.

2. As an article of manufacture, a distributing device for a locomotive stoker for distributing over a fire box fuel fed thereto, said distributing device having a longitudinal slot for emitting a jet of steam, means forming a chamber in said device for supplying steam to said slot, said chamber having opposed sides, means forming a passageway communicating with said chamber at the central back portion thereof, said passageway opening downwardly into said chamber, means in said passageway for dividing steam flowing therefrom to said chamber into a plurality of paths whereby the steam flows against one of said sides to spread out uniformly in said chamber substantially at right angles to its direction of flow through said passageway, and means in said chamber for dividing steam flowing through said chamber to said longitudinal slot into a plurality of paths to aid in the emission of steam from said slot at a substantially uniform pressure throughout the length thereof.

WILLIAM THOMPSON HANNA.
